(57) **CLAIM**

(21) Appl. No.: **29/139,498**

The ornamental design for a sun, wind and motion charging
module, as shown and described.

(22) Filed: **Apr. 2, 2001**

DESCRIPTION

(51) LOC (7) Cl. **13-02**

FIG. 1 is a front view of the present invention.

(52) U.S. Cl. **D13/102**

FIG. 2 is a rear view of the present invention.

(58) Field of Search D13/102; 60/641.8,

60/641.1, 398; 136/248, 244, 246, 205,

206, 291, 202; 126/655, 649, 629, 631,

663

FIG. 3 is a left side view of the present invention.

(56) **References Cited**

FIG. 4 is a right side view of the present invention.

U.S. PATENT DOCUMENTS

FIG. 5 is a top view of the present invention; and,

FIG. 6 is a bottom view of the present invention.
